ARRANGEMENT OF RADIALLY TRAVERSED
BLADES IN ROTARY MACHINES

Ulrich Meininghaus, Mulheim-Ruhr, Germany

Application May 17, 1933, Serial No. 671,442
In Germany June 1, 1932

15 Claims. (Cl. 253—79)

My invention relates to rotary machines such as steam or gas turbines in which a working medium flows through a plurality of blades in a radial direction, varying in pressure during such flow. The object of the present invention is to diminish the total axial thrust created by the variation of pressure with which the working medium acts on radially extended surfaces and at the same time to improve the conditions of flow.

It is known that in rotary machines provided with reaction blading large axial thrusts occur which are generally equalized by subjecting an equalizing piston provided with packing to an oppositely directed pressure of the working medium. As the packings of the equalizing piston must be arranged on a large diameter in order to expose sufficient piston surface to the pressure the packing loss, which is at least proportional to the packing diameter, is large. In the construction of axially traversed rotary machines, it is possible within certain limits to diminish the axial thrust of the blading by arranging the blades on small diameters. It is then also sufficient to construct the equalizing piston with a correspondingly small diameter whereby the packing losses diminish. Smaller diameters however involve an increased number of rows of blades if the efficiency of the rotary machine is not to be reduced. The shaft of the rotary machine is, therefore, lengthened. On the other hand, a construction of the shaft with small blading diameters does not permit of great length of the shaft in view of oscillations, in particular in view of critical speeds of rotation. Extension and thinning of the shaft, therefore, have an unfavourable effect. A limit is thus very soon reached in applying these known means for reducing clearance losses of the equalizing piston.

In cases of rotary machines with multiple housings the additional losses of the equalizing piston have been successfully avoided by letting the medium traverse the several housings in opposite directions, the now oppositely directed thrusts on the shaft being determined in such a way that they practically counterbalance one another.

The absolute thrusts on the shafts remain, however, large. Even small variations from the calculated values give rise to considerable differences in thrust which must be taken up by the thrust bearing and may destroy it. In particular, the thrusts exerted on the shaft change to different degrees when overloads occur, or when some

of the working medium is tapped off. If the absolute axial thrusts exerted on the shafts are considerable, such large difference in the oppositely directed thrusts may arise in such cases that the thrust bearing can no longer withstand them or at least is likely to be endangered. Furthermore, such an arrangement involves large demands in space and high costs in manufacture.

Still more unfavorable was the position in regard to the previously proposed constructions of radially traversed rotary machines. In order to obtain as simple a construction as possible or in order to allow the diameter of the blading to increase progressively in accordance with the expansion of the working medium during the flow through the rotary machine, it was attempted to arrange the blades on as few discs as possible as far as was permissible in view of the avoidance of overloading, by centrifugal force, of the outermost rotating blades or the devices supporting them. Preferably only one disc was used, or in cases where the above described opposed double housing was applied, one disc for each of the opposed housings. The mean diameters of the discs carrying the blading were in this way large, and, therefore, the axial thrust assumed non-permissible values. The above described disadvantages, therefore, were particularly conspicuous in the construction of radially traversed rotary machines.

According to my invention, I proceed from the conception that these disadvantages which occur particularly in the construction of radially traversed rotary machines are based on the fundamentally incorrect attempt to provide as many blades as possible on as few discs as possible, and I propose in contradistinction thereto to employ the saving in axial length resulting from the radial arrangement of the blades for arranging as many radially traversed blades as possible on the smallest possible mean diameter. According to the invention, I attain this object by distributing a selected quantity of radially traversed reaction blades among a larger number of discs than is known to be necessary for avoiding overstressing by centrifugal force of the outermost rotating blades—or the devices supporting them—or for producing oppositely directed axial thrusts. In such an arrangement I dispose only comparatively few blades on a bladed disc. The diameters of the discs are thus kept comparatively small, so that the surface offered to the pressure of the working medium and, therefore, the absolute thrusts exerted on the discs remain small. In

this way it is surprisingly easy to diminish the absolute axial thrusts, or to maintain the differential between oppositely directed thrusts within safe limits and thereby avoid any danger to the 5 thrust bearing.

By the reduction in blading diameter the further advantage is obtained that small speeds of flow of the working medium can be advantageously employed and that the hydraulic losses 10 are greatly diminished. It is known that small speeds of flow themselves result in smaller flow losses; in addition however the blade channels turn out larger themselves in consequence of the diminution of the blading diameter (diminished 15 periphery) and also in consequence of the slowing down of the flow whereby the edge losses and clearance losses diminish comparatively greatly.

On the accompanying drawings, are shown diagrammatically and by way of example various 20 constructions according to the present invention in its application to steam turbines. All of the figures of the drawings show vertical sections along the middle axis of the turbine shaft. In said drawings,

25 Figure 1 shows a multi-stage condensing turbine working with high head but with normal quantities of steam, the blading being distributed on the two shaft ends of another rotary machine, for example a generator, so as to equalize the 30 thrust;

Figure 2 shows an arrangement similar to Figure 1 but for larger steam quantities, and involving a duplicated arrangement and parallel traversal of an axially traversed blading and the 35 immediately preceding radially traversed blading in the lowest pressure stages;

Figure 3 shows the arrangement of all the 40 blades of a condensing machine on one end only of the shaft of another rotary machine, the labyrinth disc provided for equalization of thrust being arranged close to the rotating wheel which carries the axially traversed blading and in view of its weight is disposed near the bearing;

Figure 4 shows a solution which lies between 45 the solutions shown in Figures 1 and 3 in that the one shaft end of the driven rotary machine carries all the blading and the other shaft end the equalizing discs;

Figure 5 shows a condensing turbine in which 50 the steam pressure is first reduced in a Curtis blading to such an extent that with the reaction blades disposed according to the invention the total thrust does not overload the thrust bearing; and

55 Figure 6, finally, shows a turbine with a separate shaft carrying all the discs between the bearings of said shaft and provided with a coupling to drive another rotary machine.

In Fig. 1, the parts marked 1 represent the 60 bearings which carry the shaft 2 and are arranged in the housings 3. The packing between the turbine and bearing housings is effected by the labyrinth packings 4. Certain leakage quantities escape for example through the pipe 5. The shaft ends 2 are extensions of a shaft which 65 carries a rotor of a driven rotary machine, for example a generator (not shown). The free shaft ends of the shafts 2 carry a plurality of radially traversed bladings a_1, a_2, a_3, a_4 etc. The 70 rotary part of this blading is carried by the discs b_1, b_2, b_3, b_4 etc., and the stationary part by the disc c_1, c_2, c_3, c_4 etc. As may be seen from Fig. 1, the blades of the above mentioned radially traversed blading are distributed on a large number 75 of discs and the number of rows of blades of

each disc is greater than that suitable for use in one Curtis stage. The stress caused by centrifugal force in the outermost rotating blades allows at least a general use of the large outside diameters of the last traversed blades of the disc b_4 as such blades possess the maximum blade lengths and thereby the greatest centrifugal force stress. Smaller diameters are, however, preferably chosen for the other discs, especially for discs a_1 to a_5 , which are traversed by steam 10 of high pressure and which create the greatest axial thrust, in order to keep the axial thrusts small. The blades are therefore distributed on a larger number of discs than would be necessary by the general use of such large outside diameters as are possessed by the last traversed blades of the disc b_4 , the number and size of the rotating discs being such that the blades of at least one of the discs can be distributed in the form of additional rows on at least certain of the other discs without causing the diameters of such other discs to exceed the maximum permissible diameter determined by the centrifugal force at the rated speed of the machine. In 15 the same way, the provision of fewer discs would suffice for the production of opposed axial thrusts as such.

In Fig. 1, all the radially traversed bladings a_1, a_2, a_3, a_4 etc. are traversed from the interior outwardly, i. e. a substantial part which is itself 20 distributed on a number of discs.

It is important for the effective reduction of the axial thrust and for simultaneous maintenance of good conditions of flow that a substantial proportion of the reaction blades should be 25 traversed from the inside or that blades distributed among a number of discs should be provided which are traversed in a radially outward direction. It is known to be advantageous to transform a larger head in the rows of blades with increasing peripheral speed of the blades. The outermost rows of blades of the radially traversed blading therefore transform a larger head than the inner rows. On the other hand, a larger drop of pressure accompanies a given head of working medium with higher pressure of the working medium. If therefore the blading is traversed radially from outside to inside the largest drop in pressure is produced in the outermost 30 stages because the greatest head is here transformed and because at the same time the working medium on entering from outside into the outermost rows of the blades possesses the highest pressure. In the inner rows of blades the head transformed diminishes and also the pressure of the working medium whereby the drop in pressure effected by both influences is diminished. The described influences have a reverse 35 effect on each other and, therefore, act in the sense of the equalization of pressure differences in a blading traversed from inside to outside. However, the surface offered to the pressure difference of the working medium is larger in the outer rows of blades, corresponding to the greater periphery, than in the inner rows of blades, so that an increased drop in pressure towards the outside results in an increase in the total thrusts with the same total pressure drop. A blading traversed radially towards the outside is, therefore, of great importance for diminishing the 40 absolute axial thrusts of the discs. Furthermore, such a traversal involves important advantages with regard to accommodating the channel cross-sections of the blading to the progressive expansion of the working medium. 45

The discs b_1 to b_8 and c_1 to c_8 , on which radially traversed blades according to the invention are disposed, the pressure being different in at least each second row of blades, are arranged axially 5 one behind the other, i. e., they are traversed consecutively by the working medium. In consideration of the great advantages of the outwardly directed traversal, and also with regard to diminishing the heat exchange through the 10 discs, only one side of the surface of discs disposed between other discs carries radially traversed blades, the interspaces between the unbladed disc sides of adjacent discs serving for returning the working medium. Thus by the exclusive or nearly exclusive use of blading traversed radially towards the outside only one side 15 of the discs b_1 , b_2 , b_3 , b_4 , etc., and of the discs c_1 , c_2 , c_3 , c_4 , etc. is bladed, whilst the steam returns 20 on the rear side of the discs from the outer periphery towards the center.

As according to my invention often as many discs as possible are to be provided on one shaft, it is of extreme importance that stationary and rotating discs which carry radially traversed blades 25 should be of axially undivided construction whereby erection and removal take place in axial direction. If, for example, the stationary discs were axially split in order to permit of inspecting the blades by simply lifting off the upper 30 halves of the stationary blade carriers as is customary in the construction of axially traversed turbines, there would be a quite substantial limitation in the possibility of accommodating the discs. The axial split line of the discs involves a 35 very considerable weakening of the discs as tangential stresses which in the main are producers of stiffness of the discs can no longer form undisturbed but are in the main relieved by the axial joint. Discs provided with an axial split line, 40 therefore, have to be constructed of greater thickness, which construction, in the case of a plurality of discs, results in a substantial increase in the length of construction. Moreover, the provision of an axial joint in the stationary discs is 45 only advantageous when, as described above, a simple removal of the upper halves of the stationary discs is to be rendered possible. Radially traversed blades however engage one another in such a way that the halves of the stationary discs 50 can only be removed when the blading has first of all been brought out of engagement by a corresponding axial displacement. To make such axial displacement possible sufficient space must be left between the rear sides of all stationary 55 and rotating discs, which involves a further substantial increase in the total length. Finally, the provision of axial joints in the attachment of radially traversed blades has further constructional disadvantages which are particularly 60 marked when the free blade ends are supported by carrier rings as has been shown to be necessary in practical successful constructions. Therefore also the stationary discs c_1 to c_8 are all of integral construction so that tangential forces 65 arising from the axial thrusts caused by the steam pressure, resist distortion of the discs.

I have obtained a particularly compact construction of the discs b_1 to b_8 and c_1 to c_8 by arranging the parts in such manner that the radially traversed blades a_1 , a_2 , a_3 , a_4 etc. are supported by tangential annular elements or rings a' of closed construction which are connected on one side with the blades by connecting webs to form thin thermally flexible discs, the axial thickness of the webs not exceeding or not appreciably

exceeding the radial thickness of the carrier ring, as described and claimed in my copending application Serial No. 600,500. By "thermally flexible" is hereby to be understood that no special linkages between the carrier rings and the discs, 5 which would increase the axial length, are necessary in order to allow the aforesaid carrier rings a capacity of expansion or contraction on change of temperature of the working medium which is practically as great as that possessed by the carrier rings which are connected only to the blades. Such "thermal flexibility" of the carrier rings is necessary to obtain minimum packing play within the blading. By diminution of the axial thickness of the discs, therefore, a diminution of axial 10 length is effected in a double sense and multiplies itself correspondingly by the provision of a plurality of discs and thereby renders possible the accommodation of this plurality of discs. Hence the discs are rigid against thrust but can be made 15 so thin that with minimum axial length they can at once follow all variations in the thermal condition of the steam, so that the interposition of special flexible connections between the carrier rings and the discs is superfluous. 20

It appears at first as if the blading diameter of the axially juxtaposed discs could not be sufficiently accommodated to the increase in volume of the working medium. I have found, however, that surprisingly good results are obtained by a 25 correctly chosen speed of flow increasing from disc to disc when the mean diameters of the discs increase from disc to disc in the direction of flow of the driving medium. By such an arrangement, moreover, the attachment of the several discs to 30 the shaft or bush supporting them can be effected particularly advantageously by arranging that the inner diameters of the adjacent discs increase in the direction of flow of the driving medium from disc to disc by at least the breadth of one row of 35 blades. In this way it is possible to fix each disc for itself, e. g. by caulking, as the larger discs can be slid into position undisturbed over the supporting shoulders for the smaller discs.

The mean diameters of the bladings a_1 , a_2 , a_3 , a_4 , etc. are therefore made to increase from disc to disc in the direction of flow and accommodate themselves satisfactorily thereby, with simultaneous increase in the steam speed, to the increase in steam volume. Likewise, the internal 45 diameters of the discs increase from disc to disc and thereby it is rendered possible to provide on the bushes 7, carrying the rotating discs, shoulders 6 which are necessary for taking up the axial thrust of the rotating discs b_1 , b_2 , b_3 , b_4 , etc. but which do not prevent movement of the discs axially into place along the bushes.

The subdivision of the radially traversed blades among a larger number of discs does not exclude the increase of the diameter on which the 50 outermost blades of the last discs in the direction of flow of the driving medium are disposed to a limit which appears permissible in view of the stresses due to centrifugal force when, for example, large quantities of flowing working medium render this necessary. This necessity occurs particularly in steam turbines working with condensation. When additionally required, I dispose behind these radially traversed blades an axially traversed blading. In view of the substantial weight of rotating wheels which must support such axial blading, I prefer to arrange the rotating wheel carrying the axially traversed blading between a bearing and the radially traversed discs in order to relieve the shaft. 55 65 70 75

- In Fig. 1 the external diameter of the last radially traversed disc b_8 is extended up to the limit which appears permissible in view of centrifugal stress. The large surface of these discs has practically no influence on the magnitude of the axial thrust, as the steam pressure here is already very low. On the other hand, a large blading diameter is much desired in this place in view of the large steam volumes. The volume in the last low pressure stages of the turbine is already so large that an axially traversed low pressure blading 8 is provided. The rotating blades of this low pressure blading are arranged on a rotating wheel 9 and the stationary blades on an axially divided ring 10 . The heavy rotating wheel 9 is disposed, in view of the load on the shaft end due to its very great weight, between the bearing 1 and the radially traversed discs b_6 , b_7 and b_8 .
- Fig. 1 shows an overhung arrangement of the radially traversed discs b_1 , b_2 , b_3 , b_4 , etc. on the shaft ends 2 of the rotary machine (not shown), e. g. a generator. Quite special advantages result from such overhung arrangement of the radially impinged discs on the shaft ends of rotary machines, for instance, packing of the shaft against the full pressure of the working medium may then be completely avoided. The most valuable machine results, however, when radially impinged discs are disposed in an overhung manner on both shaft ends of another rotary machine as shown in Fig. 1. The opposed construction as described above for axially traversed rotary machines can then be employed and all packing against full working pressure can be dispensed with, but notwithstanding, a disproportionately large number of radially traversed blades are accommodated on a number of axially juxtaposed discs whereby the absolute axial thrust is kept within permissible limits.
- The overhung arrangement of the discs involves the further advantage that a simpler, cheaper and more compact total construction is obtained. The enclosed machine unit can be supported in the simplest way—for example in case of steam turbines—on the condenser and can therefore often be shipped in the built-up condition whereby substantial foundation and working costs are saved. In particular there is no coupling up of separately journalled power transmitting shafts and the single shaft which is supported in two bearings only can be balanced so as to be practically free from oscillation, such condition not being disturbed by any coupling with power-transferring shafts.
- The same idea of diminishing axial thrust can be applied to the packings between working medium and bearing oil. To this end I arrange that corresponding to the axial juxtaposition of the radially traversed blade carrying discs the packing devices, which in known manner possess radially arranged throttle positions, should consist of several axially juxtaposed discs.
- The labyrinth clearances in the steam packing are accordingly divided among several rotating discs d_1 and d_2 as well as stationary discs e_1 , e_2 , in order to keep small the axial thrust of these discs.
- In Fig. 1 the rotating discs b_1 to b_8 are distributed upon the two shaft ends 2 of a rotary machine for reasons above described. The steam enters in the high pressure housing 11 at 12 , flows consecutively from the interior outwardly through the blades a_1 to a_8 , and leaves the housing again at 13 . The pipe line 13 leads the steam into the low pressure housing 14 , and the steam flows consecutively through the bladings a_6 , a_7 , a_8 , and 8 and finally escapes through the exhaust steam pipe 15 . As the steam pressure decreases within the bladings a_1 , a_2 , a_3 , a_4 , etc., a lower pressure is exerted on the rear sides of the rotating discs b_1 to b_8 than on the bladed sides of the discs and consequently oppositely directed axial thrusts arise which are equalized through the shaft of the driven rotary machine (not shown). In the case of the stationary discs c_1 to c_8 , however, a higher pressure is exerted on the rear than on the bladed side, so that an axial thrust in the same direction, as in the case of the rotating discs, arises which is equalized through the housing of the rotary machine (not shown). Any differences in thrust which arise are small as the absolute values of the axial thrusts are small in consequence of the small diameter of the high pressure discs. They can without danger be taken up by the thrust bearing (not shown) of the rotary machine, such as a thrust bearing of the type shown at 27 in Figs. 4-6.
- The above described devices concern principally discs with radially traversed blading, which are juxtaposed axially and traversed consecutively by the working medium. The stated constructions meet difficulties, however, when driving media of very large volume are to be operated with, in particular in the construction of the low pressure blading. It is known to reduce the blade lengths necessary for operating with driving media of large volume by arranging that the blade groups are multiple and are traversed in parallel, axially traversed blade groups being conveniently disposed after radially traversed blade groups, as these can be constructed with larger admission diameters.
- Parallel traversed blade groups in the case of radially traversed blades which, as is known, are advantageously supported at both ends by closed carrier rings, can be amplified up to certain limits by the provision of blade rings additional to the head rings of blade rings already supported on one side of the blade carriers. This juxtaposition of blade rings soon reaches a limit, however, in view of the danger of oscillations and of overstressing by the sum of the torques. Besides, the blade length of axially traversed blade groups which, as shown in Fig. 1, sometimes follow the radially traversed blade groups cannot be increased in this manner. One is therefore compelled to arrange separate blade carriers parallel to one another and to provide between them the necessary space for the inflow and outflow of the driving medium.
- Such an arrangement cannot, however, advantageously be accommodated on an overhung shaft end as those blade groups which must operate with driving medium of large volume, and consequently possess large diameter, considerable blade lengths and large weight, must be arranged in the immediate neighborhood of the bearing in view of bending and critical speed of revolution of the shaft end. The parallel arrangement of such blade carriers on one and the same shaft end would result in non-permissible wide spacing of at least one of the blade groups from the bearing.
- In a further development of the invention I therefore propose that rotating wheels carrying axially traversed blading be arranged on both shaft ends of another rotary machine between the bearings and radially impinged discs. The axially traversed bladings are then traversed in

parallel in known manner. Hereby one half of two parallel blade groups traversed in radial direction can be disposed in front of each of the parallel blade groups which are traversed in axial direction. The above given points of view are ruling in selecting the suitable arrangement. It is found, however, that the new arrangement according to the invention is of great importance for the particularly heavy axially traversed stages which require a particularly large inlet and outlet cross section, the best results arising when these divided and parallel traversed axial stages are disposed at the rear of similarly divided and parallel traversed radial stages.

15 It is not advantageous in the case of rotary machines which are to be operated with a normal total head of the driving medium, to construct both sides completely symmetrical, i. e., to divide all the blade groups and to traverse them all in parallel. Not only would in this case the blade length be small and the clearance losses great in those blade groups in which the driving medium possesses high pressure and small volume, but it would above all be difficult to accommodate on each side the total number of stages necessary for satisfactory utilization of the full head. It is therefore important to employ the double flow, i. e. the parallel arrangement of the blade groups in the region of great volume of the working medium, i. e. preferably in the region of low pressure, and in the remaining part of the blading on the other hand to employ the single flow with provision of as many consecutive stages as possible. In view of the great importance of this task, I construct the apparatus in such a way that the blade groups which are first traversed by the working medium entering the machine are arranged near the one half of the parallel traversed blade groups on the same shaft end, and that the blade groups traversed next by the working medium flowing out of the above blade groups are located near the other half of the parallel traversed blade groups on the other shaft end. In this way, I obtain the best possible distribution of the blade groups in relation to bending and critical speed of the shaft end, as now the heavy blade groups which operate with driving medium of large volume can be disposed in the immediate neighborhood of the bearings, whilst the preceding light stages are located at the ends of the shaft where they may be provided in greater number in consequence of their light weight.

20 In order to be able to dispose the so arranged blade groups in series in large number at the beginning of the transformation of energy of the working medium and in parallel at the end of the transformation of energy, I propose, as a further development of my invention, to carry out the operation in such a way that the total working medium as far as it transforms its full energy in the rotary machine is led after partial transformation of energy from one shaft end of the driven rotary machine to the other shaft end, and that a part of the working medium after further, but not yet complete transformation of energy flows back again to the first mentioned shaft end, whereby the remaining transformation of energy of the working medium takes place at both shaft ends. A tapping off, if such is required, is neglected in the above description.

25 One embodiment of this form of my invention is shown in Fig. 2 which is differentiated from Fig. 1 in that the steam after traversing the bladings a_1 , a_2 , and a_3 is transferred through the pipe 13

from the high pressure housing 11 to the low pressure housing 14. Here the whole mass of steam flows through only the bladings a_4 and a_5 whereupon only one half of the steam traverses the bladings a_6 and 8 whilst the other half is led back to the high pressure housing 11 through the pipe 16. This steam then traverses the bladings a_7 and $8a$, i. e. the bladings a_6 and 8 as well as the bladings 8 and $8a$ are traversed in parallel by steam of the same pressure as otherwise the blade lengths would become very large in consequence of the large volume of steam. Between the steam leaving the blading a_3 and the steam entering the blading a_7 a packing 17 must naturally be provided which is constructed of packing clearances distributed on discs. The steam finally flows away through the two exhaust connections 15 and 15a. The arrangement shown in Fig. 2 has the particular advantage that the bladings a_1 , a_2 , a_3 , a_4 , and a_5 traversed by steam at high pressure possess a low traversal diameter in consequence of the axial juxtaposition of the radially traversed discs b_1 , b_2 , b_3 , b_4 and b_5 , and therefore small axial thrusts and large blade lengths are realized, whilst in the region of low pressure, on the other hand, bladings a_6 , a_7 , 8 and $8a$ traversed in parallel by large steam volumes can come into use. This ensures favorable distribution of weight and equalization of thrust. In other respects, all that has been said in connection with Fig. 1 applies just as well to Fig. 2. It applies also to the following Figs. 3 to 5 with the exception that in these figures all blades are arranged on one and the same overhung shaft end and that the axial thrust is equalized in different ways by special arrangements.

30 The advantages of diminution of the absolute axial thrust by the disposition of the radially impinged discs in series according to the invention arise also when the axial thrust is equalized by special labyrinth pistons or labyrinth discs. If, however, the advantages are to be fully realized, great care must be taken that good packing conditions exist for the labyrinth pistons or discs. It is important to keep small the overhang of the free shaft end of the rotary machine as this exercises great influence on the possibility of maintaining the extremely fine packing play. Even in a two bearing system, such as is obtained by an overhung arrangement, oscillations of the shaft cannot be completely avoided. The movements of the shaft produced by such oscillations grow in proportion to the distance from the bearing centre and produce, therefore, with increasing overhang an increasing wear on the packing points and, thereby, an increasing enlargement of the packing play whose maintenance at low values on the other hand is of extreme importance for the attainment of high efficiency. In recognition of this fact, it has already been proposed to dispose the parts which are most sensitive in regard to the maintenance of packing play as close as possible to a bearing. In machines with a pressure equalizing disc this applies first to such disc, furthermore to the high pressure stages in which the volume of the working medium is still small. With decreasing pressure, i. e. increasing volume, the harmful effect of a possible increasing clearance diminishes more and more. In machines in which axial thrust is taken up by a pressure equalizing disc provided with labyrinth, therefore, an arrangement of the pressure equalizing disc in the immediate neighborhood of the journal has proved of value, the driving medium flowing to the blading in the direction from the

bearing. If several radially impinged discs are provided, the blading in which the working medium possesses already the greatest volume is then located further distant from the bearing.

5 In rotary machines with very large final volumes in which the last stages must be carried out with axial traversal, such an arrangement has hitherto appeared impossible. The wheel carrying the axially traversed low pressure stages is so 10 heavy that it is disposed near to the bearing if harmful bending of the shaft end is to be avoided. As an example of such a case, steam turbines for condensation operation may be mentioned.

In a further development of my invention I 15 provide a new arrangement which permits of disposing the pressure equalizing disc and low pressure wheel in close proximity to the bearing. This arrangement consists in disposing a pressure equalizing disc with axial thrust in the direction 20 towards the bearing next to the rotating wheel which is arranged between the bearing and the radially impinged discs and carries the axially traversed blading so that the equalizing disc is located between axially and radially impinged 25 discs or rotating wheels. This arrangement involves the further advantage that the rotating equalizing disc, which is constructed with very thin walls owing to the required thermal flexibility, lies against the rotating wheel carrying the axially 30 traversed low pressure blading, so that the axial thrust is transferred from the equalizing disc to the rotating wheel. A special support for the flexible equalizing disc can be dispensed with as the very strong rotating wheel can take up the 35 axial thrust without being overstressed.

In Fig. 3, therefore, in contradistinction to Figs. 1 and 2, all the blading parts and devices for equalization of thrust are disposed on one overhung shaft and only of a rotary machine 40 (not shown). Here again the radially traversed bladings a_1 , a_2 , a_3 , and a_4 are arranged in axial juxtaposition and behind them is disposed an axially traversed blading 8 . One of the novel features of the construction of Fig. 3 is the thrust 45 equalizing discs $18a$ and $18b$ with the labyrinth 18 . In order to give these a minimum overhang-distance from the bearing 1 —they are disposed immediately next to the heavy rotating wheel 9 carrying the blading 8 for which its part 50 is arranged facing the bearing in consequence of its large weight.

A so-called regulating stage (action stage) for improving the part-load efficiency may be disposed in front of the high pressure reaction 55 blading, but the space available for this purpose with normal constructions is not sufficient. The space required for axially directed inflow and outflow of the working medium is too large. In order to render possible the arrangement according to the invention I provide, therefore, the regulating stage as a radially traversed stage and obtain the space for the provision of the equalizing discs $18a$ and $18b$ between the high and low pressure wheels. In this way there results outside the action wheel also sufficient space for a corresponding arrangement of the nozzle groups 20 without the axial length needing to be increased to a non-permissible extent. The quantity of working medium flowing out flows inwardly directly to the first radially traversed high pressure stages a_1 which are traversed from outwards inwardly and are advantageously arranged within the action stage 22 .

As the working medium leaving the high pressure blading a_1 at the free end of the shaft in

consequence of its great volume is led to the low pressure blading 8 through conduits 23 which surround the whole machine as a closed ring, special measures are necessary to lead the live steam to the equalizing disc and high pressure blading through this closed low pressure steam ring. Therefore, the driving medium is fed to the equalizing discs $18a$ and $18b$ and at the same time to the high pressure portion through pipes 19 which are disposed elastically in a space inside the housing 14 through which flows the working medium flowing to the axially traversed low pressure blading. Such pipes can easily be fitted in a pressure tight manner in the walls. As these pipes, however, are traversed by a hotter medium than the space through which they pass, particular care must be taken that the considerable thermal expansion of the pipes does not exercise any harmful bending forces on the housing. These pipes are, therefore, advantageously disposed with sufficient length, e. g. in spiral form 20 in a pocket in the housing 19 through which they are to be led. This arrangement ensures with certainty avoidance of distortions and bending of the housing or the walls in consequence of unequal thermal expansion such as would have occurred if the working medium had been led to the high pressure portion through cast-in channels.

In Fig. 3, the steam enters the conduits 19 30 through pipes 12 and flows then into the nozzle chambers 20 . For effecting the known nozzle regulations several separate nozzle chambers 20 are provided. From them the steam flows 35 through nozzles 21 to an action stage 22 which is traversed radially inwards and is supported by the disc b_1 , and thus space is gained for the provision of the thrust equalizing discs $18a$ and $18b$. The steam flows through the blading a_1 from the exterior inwardly, then from the interior outwardly through the bladings a_2 , a_3 , a_4 , and is finally led through channels 23 past the pipes 19 to the blading 8 . It leaves the machine through the exhaust port 15 . Considering the axial direction, therefore, the flow of steam through the bladings a_1 , a_2 , a_3 , a_4 is opposed to that through the blading 8 . In this way it is possible to compensate for the axial thrust on the radially traversed discs b_1 , b_2 , b_3 and b_4 which outweighs the axial thrust of the rotating wheel 9 by a thrust 50 equalizing disc $18a$ disposed on the rotating wheel. The discs b_1 , b_2 , b_3 , b_4 are arranged on a common bush 1 in order to render easily accessible the equalizing discs $18a$ and $18b$ of the labyrinth 18 . This arrangement is chosen as the 55 diameters of these discs increase in correspondence with the growth in volume of the working medium with the distance from the equalizing disc. The high pressure portion must, therefore, be built together preferably from the side facing the equalizing disc (entry side). By arranging the high pressure discs b_1 to b_4 on a common bush they are built together without difficulty separately from the shaft and then the disc 9 carrying the low pressure stages on which the equalizing disc is attached, can be inserted with its hub into the bushing of the high pressure blading.

Special cases sometimes arise in which on the one hand the accommodation of the pressure 70 equalizing disc on the same shaft end as the discs arranged axially behind each other between the latter and the bearing, has disadvantages or causes difficulties, but on the other hand the equalization of thrust by distribution of the bladed 75

discs on both shaft ends of the rotary machine does not appear justified from economical considerations or meets technical difficulties in construction. For example, in case of large quantities of working medium the transfer pipes, which must convey the total working medium from the one side to the other side after it is increased in volume to a large extent by expansion in the first housing, assume considerable dimensions. These 5 large pipes which in practice elongate differently from the rotary machine over which they bridge, exercise considerable bending forces on the whole construction and may in certain circumstances cause disturbing displacements. Special expansion pieces must therefore be provided which must possess, together with sufficient power of resistance to the high pressure of the working medium, also sufficient resilience. Sometimes space is lacking for the accommodation of the large transfer pipes. Finally, in many cases intermediate arranged auxiliary machines hinder the transference of large torques of the rotary machine from or to both shafts ends. Also the packing of the shaft against the exit pressure of the 10 high pressure housing may involve perceptible losses in working medium. In addition, disadvantages or difficulties can arise from the accommodation of the pressure equalizing disc between the bladed discs and the bearing in such special cases. For example, the working medium must be introduced into the rotary machine from the periphery. If the working medium is very hot it heats up the housing one-sidedly and causes disturbances of the housing and therefore displacements of the stationary blading disposed outside the bearing. Besides, the overhang of the blading is increased by the interposition of the equalizing discs, whereby when very many discs are 15 arranged the above described enlargements of clearance now occur in the blading itself. The saving in losses in the equalizing labyrinth, which is obtained by disposing the equalizing disc in the neighborhood of the bearing may therefore be cancelled to some extent in cases of arranging very many discs on one shaft and owing to increased losses in the blading. There is also the important practical difficulty that the high temperature of the entering working medium are introduced near to the bearing.

20 In Fig. 4, therefore, discs b_1 to b_4 and c_1 to c_4 carrying axially juxtaposed radially traversed blading a_1 to a_4 are arranged on one only of the two shaft ends 2 of another rotary machine (not shown) whilst on the other shaft end are disposed rotary bodies 24b and 25b carrying packing 24 and 25 traversed by the driving medium which serve for the equalization of the axial thrust. The arrangement according to Fig. 4, therefore, 25 renders it possible to dispense with the large transfer pipes and to feed to the rotary bodies disposed on the one end of the shaft only so much driving medium as is necessary to equalize the axial thrust which is produced from the blade portions disposed on the other end of the shaft.

30 Furthermore, both ends of the shaft are to be packed only against the low back pressure of the working medium. It is, therefore, possible to arrange the blading as well as the thrust equalizing device close to the bearings 1, and the torque is transferred only through one end of the shaft, the other end being relieved from the torque and thus available for disposing auxiliary devices.

35 In Fig. 4 a larger number of blades than in Fig. 3 is distributed among the same number of rotating discs b_1 , b_2 , b_3 , b_4 . According to this

part of the invention, the bladings a_1 , a_2 , a_3 and a_4 are hereby arranged in the most advantageous way, i. e. they are all traversed from the inner diameter outwardly. Hereby an advantageous arrangement of the pressure equalizing discs 24a, 24b, 25a, 25b with the labyrinth 24, 25 on the same shaft end with the bladed discs is rendered impossible. On the other hand a division of the blading between the two shaft ends is not effected, whereby for example manufacture is made 10 cheaper and the provision of large transfer pipes together with the transference of torques through both shaft ends is avoided. The rotary thrust equalizing discs are provided on the other shaft end where they are advantageously located near 15 the bearing. Only a very small pipe 26 is provided for conveying to the second shaft end the steam necessary for the equalization of thrust. Fig. 4 also shows the thrust bearing 27 necessary for taking up the difference in thrusts.

The arrangement of pressure equalizing discs and the leakage losses of working medium caused by them may in many cases be avoided in turbines provided with an action blading as shown in Fig. 5. Here the steam enters by pipes 12 and expands to a comparatively low pressure in the nozzles 21. The steam then impinges the action blades 22 which comprise two velocity stages (Curtis blading) supported by the disc 28, and flows through the radially traversed blades 30 a_1 , a_2 , a_3 and the axially traversed blades 8 leaving the machine through the exhaust port 15. The total thrust created by the action of the low pressure on the discs b_1 , b_2 , b_3 and on the wheel 9 is small and easily taken up through the shaft 2 by means of the thrust bearing 27. This construction is especially suitable for small machines with low admission pressure, as with the aid of axial juxtaposition of several consecutively radially impinged discs according to the invention 40 it is possible in many cases—especially when action stages are first traversed—to diminish the axial thrust to such an extent that it may be taken up by a thrust bearing 27 so that all losses of working medium for the purpose of thrust 45 equalization may be avoided. In order to be able to accommodate a sufficient number of discs on the shaft ends the axial thrust is equalized through the shaft 2 of the rotary machine which carries the discs in an overhung manner. The 50 thrust bearing 27 is accommodated on the other side of the rotary machine from that which carries the discs in an overhung manner so that the whole space outside the bearing is available for accommodation of the discs carrying the 55 blades and packing.

In Fig. 6 the inventive idea is applied to a condensing turbine in which the discs b_1 , b_2 , b_3 , b_4 , b_5 and 9 supporting the blades a_1 , a_2 , a_3 , a_4 , a_5 and 8 are arranged on a special turbine shaft 2 between two bearings 1 according to the standard practice with axially traversed turbines. The steam enters the housing 11 at 12, flows consecutively through the blades a_1 to a_5 and 8 leaving the housing at 15. The total axial thrust created by the action of the steam on the discs b_1 to b_5 and the wheel 9 is taken up by the equalizing discs 18a with the labyrinth 18. These equalizing discs are supported by the common bush 7 in order to render accessible the discs b_1 to b_5 which are 65 caulked directly to the shaft 2. The shaft 2 of the turbine may be coupled to a shaft 31 of any kind of machinery to be driven by means of the coupling 30.

The constructions shown have, of course, been 70

given by way of example only, and the invention is not limited thereto, as various modifications may be resorted to within the scope of the appended claims without departing from the spirit 5 of the invention. In particular, the radially traversed discs can be employed without subsequent axially traversed rotating wheels.

It may be mentioned that the arrangement of a plurality of radially impinged discs on one 10 overhung shaft is made practically feasible by means of a new method and apparatus for assembling and dismantling the machine and of correspondingly constructed packing devices as described and claimed in my copending application 15 Serial No. 661,119. The packing devices in Figs. 1-5 correspond to the packing devices shown in said copending application. In the same way the discs b_1 , b_2 , etc. and the discs c_1 , c_2 , etc. and the manner of fastening them correspond to the constructions shown and claimed in my copending application Serial No. 600,500.

By the expression "reaction (steam or gas) turbine" as used in this specification and in the appended claims, is to be understood a turbine in 25 which at least all of the rotating or all of the stationary or all of the blade rows operate with reaction (the specially arranged Curtis wheels being left out of consideration in this connection). The expression "the working medium 30 flowing in the same general direction" is intended to define the forward movement of the medium in the axial direction, that is, the sequence in which the individual radial surfaces are swept by the medium one after the other. As will be 35 apparent, the impingement of a disc in a radially outward direction corresponds to an impingement upon the opposite side of the disc with the direction of impingement reversed, that is, radially inward toward the shaft.

40 I claim:

1. In a rotary machine, such as a steam or gas turbine, the combination of a shaft, bearings adapted to support said shaft, a driven rotating machine part arranged on said shaft between 45 said bearings, rotary discs arranged on a stub end of said shaft in overhung fashion, a number of radially traversed rows of reaction blades on each of said discs, carrier rings supporting said blades at both ends thereof, and stationary bladed 50 discs cooperating with said rotary discs, the latter being arranged to be impinged in series and on corresponding sides of the discs and there being a pressure drop through said blades and along 55 said discs, the mean pressures acting upon the opposite sides of at least certain of said discs being different and thus causing axial thrusts upon said discs in the same direction, the number of rotary blades being such that they can be distributed on a smaller number of discs of larger 60 diameter without causing overstressing by centrifugal force acting on the outermost rotating blades or on the disc or discs supporting them when the discs are driven at approximately the rated speed of the machine, whereby the thrust on said discs is reduced, for a given total pressure drop, as compared with the thrust on discs carrying the maximum permissible number of 65 rows of blades.

2. In a rotary machine, such as a steam or 70 gas turbine, the combination of a shaft, bearings adapted to support said shaft, a driven rotating machine part arranged on said shaft between said bearings, rotary discs arranged on a stub end of said shaft in overhung fashion, more 75 than three rows of radially traversed reaction

blades on each of said discs, carrier rings supporting said blades at both ends thereof, and stationary bladed discs cooperating with said rotary discs, the latter arranged to be impinged in series and on corresponding sides of the discs, 5 there being a pressure drop through said blades and along said discs, the mean pressures acting upon the opposite sides of at least certain of said discs being different and thus causing axial thrusts in the same direction, the number of rotary 10 blades being such that they can be distributed in additional rings on a smaller number of discs of larger diameter without causing overstressing by centrifugal force acting on the outermost rotating blades or on the disc or discs supporting them when the discs are driven at approximately the rated speed of the machine, whereby the thrust on said discs is reduced, for a given total pressure drop, as compared with the thrust on discs carrying the maximum permissible number 15 of rows of blades, rotary bodies on said shaft, and packing devices disposed on said rotary bodies and traversed by the working medium and adapted to create a pressure drop of the working medium along said rotary bodies which equalizes the 20 thrust of said discs, said discs being arranged on only one of the stub ends of said shaft while the other stub end carries said rotary bodies.

3. In a combination comprising a rotary machine and a reaction steam or gas turbine for driving said machine and designed for operation at a definite rated speed, a shaft, spaced bearings supporting said shaft, a rotating element of said machine being arranged on said shaft between said bearings, a plurality of discs disposed 30 on a stub end of said shaft in an overhung fashion, rows of reaction blades arranged on each of said discs for radial traversal by a working medium and exceeding the number suitable 35 for use in one Curtis stage, the number of said blades being such that they can be distributed on a smaller number of discs of larger diameter without causing overstressing by centrifugal force acting on the outermost rotating rows of blades or on the disc or discs supporting them 40 when the discs are driven at approximately said rated speed, stationary bladed discs cooperating with said first-mentioned discs, a rotating wheel, blades adapted to be axially traversed arranged on said wheel, said wheel being positioned between 45 the bladed discs and a bearing, and a pressure equalizing disc for exerting an axial thrust in the direction of the bearings, said equalizing disc being arranged next to said rotating wheel and between 50 said wheel and the bladed discs.

4. The combination of two rotary machines, such as a reaction steam or gas turbine and a machine driven thereby, including a shaft, bearings supporting said shaft intermediate its ends, 55 rotating parts of one of said machines arranged on said shaft between said bearings, rotary discs arranged on both stub ends of said shaft in overhung fashion, radially traversed rows of reaction blades on each of said discs, carrier rings supporting said blades at both ends thereof, stationary 60 bladed discs cooperating with said rotary discs, there being a pressure drop along said discs through said blades, conduits for leading the driving medium to said rotary discs in such manner that the mean pressures acting upon the opposite sides of at least certain of said discs is 65 different and causes axial thrusts upon said discs in the same direction, the number of rotary blades being such that they can be distributed on additional rings on a smaller number of discs of 70 75

- larger diameter without causing overstressing by centrifugal force acting on the outermost rotating blades or on the disc or discs supporting them when the discs are driven at approximately the 5 rated speed of the machine, whereby the total thrust on said discs is reduced, for a given total pressure drop, as compared with the total thrust on fewer but larger discs carrying substantially the same total number of blades.
- 10 5. The combination of two rotary machines, such as a reaction steam or gas turbine and a machine driven thereby, including a shaft, bearings supporting said shaft intermediate its ends, rotating parts of one of said machines arranged 15 on said shaft between said bearings, rotary discs arranged on both stub ends of said shaft in overhung fashion, radially traversed rows of reaction blades on each of said discs, carrier rings supporting said blades at both ends thereof, stationary 20 blades discs cooperating with said rotary discs, there being a pressure drop through said blades, conduits for leading the driving medium to said rotary discs in such manner that the mean pressures acting upon the opposite sides of at least 25 certain of said discs is different and causes axial thrusts upon said discs in the same direction, the number of rotary blades being such that they can be distributed in additional rings on a smaller number of discs of larger diameter without causing 30 overstressing by centrifugal force acting on the outermost rotating blades or on the disc or discs supporting them when the discs are driven at approximately the rated speed of the machine, whereby the total thrust on said discs is reduced, 35 for a given total pressure drop, as compared with the total thrust on fewer but larger discs carrying substantially the same total number of blades, and rotating wheels on said shaft carrying axially traversed blades, said wheels being arranged 40 behind the last radially traversed blades and being disposed on both stub ends of said shaft between the radially traversed discs and the bearings.
6. In a rotary machine, such as a reaction steam or gas turbine, the combination of a shaft, 45 rotating discs arranged on said shaft, a plurality of radially traversed rows of blades on each of said discs to be impinged by a working medium and exceeding the number suitable for use in one Curtis stage, stationary bladed discs cooperating 50 with said rotating discs, and annular elements supporting the rotating blades at both ends thereof, the pressure being different in at least each second row of said blades, the rotating discs being arranged to be impinged in series and on corresponding sides of the discs, the working medium 55 flowing at different average pressures along the two sides of at least certain of said discs and in the same general direction, thus exerting axial thrusts upon said shaft in the same direction, said 60 blades being distributed among such a number of discs whose diameters are considerably less than the maximum permitted by the centrifugal force acting at the rated speed of the machine that the blades of at least one disc can be distributed upon 65 the other discs without causing their diameters to exceed said maximum, whereby the sum of the thrusts exerted upon the shaft is reduced for a given pressure drop, as compared with the sum of the thrusts on a smaller number of larger discs.
- 70 7. The method of reducing the total axial thrust on a plurality of discs having radially impinged rows of reaction blades at the corresponding sides thereof, the rows exceeding the number suitable for use in one Curtis stage, the average pressures 75 on the opposite sides of each disc being different
- and the resulting thrusts being in the same direction, which comprises distributing the blades necessary to effect the required pressure drop through the machine upon such a number of discs having outer diameters considerably below the 5 maximum permitted by the centrifugal forces acting at the rated speed of the machine that the blades of at least one of the discs can be distributed in an additional row or rows on the remaining discs without causing increase of the 10 outer diameter of such discs beyond said maximum diameter.
8. Apparatus according to claim 6, wherein the mean diameter of said discs increases from disc to disc in the general direction of flow of the 15 working medium.
9. Apparatus according to claim 6, wherein the inner diameter of the discs increases from disc to disc in the general direction of flow of the working medium by at least the radial width of one 20 blade row.
10. Apparatus according to claim 6, wherein the outer diameters of the discs increase from disc to disc in the general direction of flow of the 25 working medium.
11. The combination according to claim 8, wherein the sum of the axial thrusts created by the action of the working medium on said discs is equalized through said shaft and taken up by oppositely acting mechanism at the other end of 30 said shaft.
12. The combination according to claim 5, wherein said axially traversed blades are traversed in parallel, while the blades first radially traversed by the working medium entering the 35 machine are disposed near the one half of said axially and in parallel traversed blades on the same stub end of said shaft, and the blades radially traversed by the working medium leaving said first radially traversed blades are disposed 40 near to the other half of the axially and in parallel traversed blades on the other stub end of said shaft.
13. The combination according to claim 5, including means for transferring the total working 45 medium transforming its whole energy in said blades, after partial transformation of its energy at one stub end of said shaft, to the other stub end, and means for conveying part of the working medium after further but not yet complete transformation of energy at said other stub end back 50 to said first mentioned stub end, the transformation of the remaining energy of the working medium thus taking place at both stub ends.
14. In a rotary machine, such as a reaction 55 steam or gas turbine, the combination of a shaft, rotating discs arranged on said shaft, a plurality of radially traversed rows of blades on each of said discs to be impinged by a working medium in the radial direction and exceeding the number 60 suitable for use in one Curtis stage, stationary bladed discs cooperating with said rotating discs, annular elements supporting the rotating blades at both ends thereof, there being a pressure drop 65 along said discs through said blades, and conduits for leading the driving medium to said rotary discs in such manner that the mean pressures acting upon the opposite sides of at least certain 70 of said discs are different and cause axial thrusts upon said discs in the same direction, the number of rotary blades being such that they can be distributed on additional rings on a smaller number of discs of larger diameter without causing overstressing by centrifugal force acting on the outer- 75

most rotating blades or on the disc or discs supporting them when the discs are driven at approximately the rated speed of the machine, whereby the total thrust on said discs is reduced, 5 for a given total pressure drop, as compared with the total thrust on fewer but larger discs carrying substantially the same total number of blades.

15. A rotary machine as set forth in claim 14 wherein the diameters of the successive discs increase in the direction of fall of pressure of the working medium, the higher pressures thus acting on discs of smaller diameters. 5
